CLAIM

We claim the ornamental design for a display screen including a dental laser graphical user interface, as shown and described.

DESCRIPTION

FIG. 1 is a front view of a display screen including a dental laser graphical user interface showing a first image; and, FIG. 2 is a front view of a display screen including a dental laser graphical user interface showing a second image. The appearance of the transitional image sequentially transitions between the images shown in FIG. 1-2. The process or period in which one image transitions to another image forms no part of the claimed design.
